COMBINATION WATER SOFTENER AND HEATER WITH REVERSE FLUSH

Filed July 15, 1942

UNITED STATES PATENT OFFICE

2,355,188

COMBINATION WATER SOFTENER AND HEATER WITH REVERSE FLUSH

William J. Towles, Los Angeles, Calif., assignor to himself and Donato F. Sisto, Los Angeles, Calif.

Application July 15, 1942, Serial No. 451,005

7 Claims. (Cl. 122—16)

This invention relates to devices used for heating water in conjunction with a softening apparatus.

One of the objects of this invention is to provide a water heater with a distinct and easily accessible water-softening apparatus.

Another object is to provide a water heater with an easily removable and exchangeable water-softening apparatus.

Another object is to provide a water heater of such a type whereby a heating element of a commonly-known heat-spreader may be used advantageously.

Another object is to design and arrange the individual parts and the whole softening apparatus so that such parts or the whole apparatus may be removed or exchanged without difficulty from the water heater; particularly without otherwise affecting the water heater as such.

Other objects will appear from the following description and appended claims as well as from the accompanying drawing, in which—

Fig. 1 is a vertical midsectional view of a combination water softener and heater embodying this invention.

Fig. 2 is a fragmentary detail vertical section of a slightly modified form of pipe support.

Fig. 3 is another modified form of such support.

Fig. 4 is still another modified form of support.

Fig. 5 is still another modified form of support.

Fig. 6 is a fragmentary cross section on line 6—6 of Fig. 1, of the supporting-ring within the casing.

It is a simple fact that devices commonly known as "heat spreaders" are very cheap to manufacture, on the one hand, and, as a general rule, quite easily and simply applied to the average water heater, such as are in common use in households.

At times, the preferred material for coils is difficult to obtain; while material for the so-called common heat spreaders may be quite readily obtainable.

The herewith submitted combination water heater and softener is of such a construction and arrangement that either of the two above-named heating elements may be used with equal efficiency. This also allowing the use of other similarly applicable devices, such as electric heating elements, as should easily be understood without further explanation or illustration.

The whole combination water heater and softener of the present invention is moreover designed and arranged so that certain parts are advantageously intercooperating with other parts,

as should be evident from the following description.

Having indicated at 1 a common gas burner for supplying the heat; from the above, it should be understood that other heating facilities can easily and with equal efficiency be substituted.

For a thermostat, also, any type, easily to be had on the open market, or easily manufactured, may be applied in its proper place, not necessarily at the point indicated at 2 in the drawing, nevertheless to act co-operatively at 3 or at other suitable points with reference to any eventually used heating device.

The eventually selected type of heat spreader 4 is then co-operatively, or suitably, arranged to properly serve in this present case.

As illustrated, the heat spreader 4 has a communicating connection 5 with the inside of the shell 6 of the water heater for its water intake, and an outlet connection at 7. The outlet-connection, in this case, is preferably in form of a heating element 8, extending upwardly to discharge by another connection at 9 through the wall of the flue 10 into the upper part of the water heater compartment.

This heating element 8 is advantageously disposed within the gas exhaust flue 10, whereby the products of combustion from the burner 1 pass around the whole length of the heating element 8 before such products pass out of the flue 10.

The exhaust flue 10, and therewith the heating element 8 are preferably arranged in the inclined position as illustrated, to thereby let the products of combustion be retarded in their movement upwardly. It should be understood that the exhaust flue 10 may be comparatively narrow while the heating element 8 may be rather large in order that the annular space between them may be small, the proportions shown in the drawing of the two tubular members being merely for illustration.

As illustrated, the water heating compartment is enclosed by the shell 6, the bottom 67, and the apertured top 70, the shell 6 being surrounded by a jacket 71 to provide for more easily retaining the heat in the water compartment, no particular insulating means being claimed in this case since such possibilities are of general knowledge.

At any suitable place within the water compartment within shell 6, a water softening apparatus is arranged as illustrated.

This softening apparatus has its own casing 11 with a closing bottom 12. Two short pipe-sections 15 are provided for purposes more fully

described later on. These pipe-sections are mounted and secured in the bottom by the lock-nuts 13 and the cap-nuts 14.

A spacing ring 16 is placed in the bottom end of the casing for supporting a filtering medium spacedly above the bottom within the casing; and two pipe-couplings 17 are provided for connecting other pipe sections 23 to the upper ends of the pipe-sections 15 and for suitably compacting the filtering medium.

The filtering medium may consist of coarse and fine gravel, or any other suitable material, depending on the purpose or use for which the medium may be intended; in the illustration, a layer of fine material 21 being disposed between the lower layer 20 and the upper layer 22 of coarse material; the several layers being held in place between the lower screening disc 18 and the upper screening disc 19; the whole being compacted, as already stated, between the spacing ring 16 and the pipe-couplings 17.

Longer pipe-sections 23 extend from the couplings 17 upwardly through the top end of the casing 11. In fact, the longer pipe-sections 23 and the shorter pipe-sections 15 form co-operating and supplementing means by which a layer of softening medium and other filtering layers, besides those already referred to, are held together within the casing 11; and also whereby the cover 33 is held firmly against the top of said casing; the supplementing pipe sections serving also to conduct water in the proper direction and manner through the softening apparatus when in operation.

A water-softening medium 24 extends from the upper screening disc 19 to the level indicated at 25.

Provided above the level 25, a sectional supporting-ring 26, illustrated in Fig. 6, forms the support for additional filtering material; a screening disc 27 resting on the ring-sections 26a, a coarse filtering body 28 resting on the disc, a finer filtering body 29 resting on body 28, and another coarse filtering body 30 resting above body 29, these filtering bodies being compacted together by another screening disc 31 under the flange 32 of the cover 33. The sectional shoulder-ring 26 is secured to the inner wall of the casing 11 in any suitable manner, as by riveting, welding, or spot-welding.

Packing rings 34 and washers 35 seal around the upper pipes, and the cover is clamped down by means of the nuts 36 on the pipes.

A flange 37 is secured by welding or otherwise to the outside of the casing 11, a suitable distance below the upper end of the casing, by which the casing is secured in proper position within the shell 6, by means of the bolts 38.

From the foregoing, it should be easily understood that the different parts of the softening apparatus can be assembled while still outside of the water-heater; and also—that the different parts can easily be removed, exchanged, or replaced even after the softener and heater have been assembled.

Before the softener is put into the heater, the filtering medium 20—21—22 may be inserted from the lower end of the casing 11 and the filtering material and screens may be clamped together between the couplings 17 and the cap nuts 14. The pipe-sections 23 and 15 may then be connected by means of the couplings 17.

At this juncture, the casing is turned upright, to allow and provide for the insertion of the softening medium 24 and the additional layers of

filtering medium 28—29—30 from the top-end of the casing.

The filtering material and screens for the lower part of casing 11 may however be inserted from the top-end, and even while the casing is in the shell 6.

The sectional shoulder-ring 26 is made in its particular form, in two parts, leaving two considerable spacings between the lateral ends 26a on opposite sides of the casing 11.

This serves to allow the insertion of the upper disc 19 of the lower filtering material. The disc is simply turned flat in the direction of the axis of the casing so that the disc may be passed through the spacings.

After passing through the spacings, the disc 19 is turned horizontally again, for proper locating over the top of the filtering material in the bottom of the casing. The couplings 17 may be firmly secured to the lower ends of the pipe-sections 23 so that the couplings may be screwed down upon the pipe-sections 15 and therewith upon the disc 19, for a proper compacting of the filtering medium.

The couplings may even be welded, in spots, to the ends of the pipe-sections 23, to thereby assure the desired disconnection from the short pipe-sections at any time that the lower filtering medium is to be removed or inspected.

The lower and shorter pipe-sections 15, too, may be welded, or spot-welded to the cap 12 in order to assure their remaining in the bottom of the casing when the upper and longer pipe-sections 23 are removed, as illustrated in Fig. 3 at 35 15b.

With the whole softening apparatus filled, or properly charged and sealed, the outside pipe connections may then easily be applied as illustrated.

T-fittings 39 and 39a, and valves 40 and 41 are applied to the upper ends of the pipe-sections 23, an elbow 42, a T 43, and a union 44 are added and connected so that fresh water may be made to pass into the water heater by way of the valve 40 or the valve 41, for purposes more fully described later on, the pipe-end 45 being the inlet for the whole combined water-softener and heater.

Other pipe fittings are provided, such as the T 46, valve 47, elbow 48, valve 49, union 50, communicating pipe 51, and discharge pipe 52. These represent the essential parts for the principal water passage through this combination softener and heater.

Softened water may be drawn by opening either the valve 47, or the valve 49; the opening of the valve 47 resulting in a discharge of cool water in the direction of the arrow 53; while the opening of the valve 49 results in a passing of the cool softened water into the heating compartment in the direction of the arrow 54.

From this it will be understood that cool water may be procured from this apparatus in a softened condition as well as heated softened water, for the purposes more fully described hereafter.

When the valves 47 and 49 are closed the fresh water will pass through the pipe fittings 43, 44, 42, 40, which is open, 39, into the pipe sections 23 and 15, on the left hand in the drawing.

At the lowermost end of the left hand pipe-section 15 apertures 55 are provided, by which the fresh water will enter the softener, to then pass through the filtering and softening mediums 75 upwardly, to reach the upper end of the softening

apparatus, at which point the upper end of the other right hand pipe-section 23 is provided with apertures for discharge of the softened water.

Coming from the softener, the water passes through the pipe fittings 39, 46, 48, 49, which is opened, 50, to finally enter the water heater by way of the pipe-connection 51, discharging at 54.

The softened water is then heated by passing in the direction of the arrow 57 into the spreader 4, from which it escapes in the direction of the arrow 58, into the additional heating element 8 within the flue 10, from which it re-enters the water heater near the upper part, as indicated at 59 by an arrow, to allow a drawing of hot softened water through the outlet pipe connection 52.

Water softeners are preferably cleaned and refreshed at suitable intervals. Some times, a mere flushing in the reverse direction of the normal flow is sufficient; while, at other times, the softening medium may have to be replenished.

Extra connections are therefore provided by which such flushing and replenishing can be accomplished; there being a pipe connection 60, an ejector 61, a control-valve 62, a test-valve 63, a connecting pipe 64, and another control valve 65.

For merely reverse-flushing the softening apparatus, all the valves excepting 41 and 62 are closed, the test-valve 63 having a side communication with the connection so as not to interfere with the flow through that pipe-connection.

The reverse-flow, then, passes from the inlet at 45 through the valve 41 so as to let the fresh water enter through the apertures 56 from the top end of the softening apparatus, downward through the softening and filtering material through the apertures 55 into the left hand pipes 15 and 23 and out of the softener by way of the valve 62.

A refreshing of the softening apparatus, by suitable salts, is accomplished by closing all the valves excepting 65, 66, and 62. The pipe-connection, controlled by the valve 65 is extended into a salt-solution holding container, not shown in the drawing since of no material importance to the described apparatus, and the fresh water is then allowed to act on the ejector 61 by way of the valve 66 and the pipe connection 60 until the salt-solution is drawn from the container through the softening apparatus in the direction of the fittings 48, 46, 39, downwardly through the apertures 56, and upwardly through the apertures 55 after having passed through the filtering and softening mediums, to escape through the valve 62 and the ejector 61.

The passing of the salt-solution can readily be tested by means of the test-valve 63.

When the several small illustrations in the drawing have been designated as modifications, it should really be understood that they, in fact, merely represent choices according to individual tastes, or may even be required under certain conditions, or in certain localities.

The welding of the lower ends of the short pipe sections 15b to the cap 12b at 69, as illustrated in Fig. 3, has already been referred to, and may be so indicated as mere choice.

Instead of the lock-washers and cap-washers 13 and 14, there may be a nipple 18, welded into the bottom 12a, into which the short pipe-sections 15a are secured, as illustrated in Fig. 2, to be plugged as at 68. The short pipe-sections 15c may even be directly screwed into the bottom 12c, and, if the bottom is not of sufficient thickness, a

plug 68c may be put into the inside of the pipe end, as illustrated in Fig. 4. Fig. 5 merely shows one of these changes adapted to the inclined bottom 67a.

It also is merely a matter of choice to put the apertures 56 in the left hand pipe-section instead of in the right hand pipe-section, so as to be in the inlet line, whereby the fresh water will be caused to spread over the disc 31 before passing through the filtering and softening mediums.

The apertures 55 are then, naturally put in the right hand pipe-section at the bottom instead of in the left hand pipe section.

Under certain conditions, this arrangement may even be of advantage, since the reversing flush will then come in an upward direction; and—since the flushing may be produced at a somewhat forced rate of velocity—the softening medium may be caused to loosen up, by rising to a suitable extent, and thereby shaking off matter that may have accumulated during the normal downward filtering and softening; the special spacing between the screening disc 21 and the normal level 25 being provided for that very purpose.

On the other hand, some one might suggest that during the upward passing of the water, it may absorb beneficial matter from the softening medium more readily when the softening matter is kept in a loose condition and actually shaken up and agitated while the water is passing through the softening medium in the upwardly direction.

Nevertheless, it is a mere matter of choice, and should be so understood.

Having thus described my invention, I claim:

1. In a water heater and softener, a shell of an elongated upright form with a bottom and top, means for heating the contents of said shell, a flue extending from the bottom in an inclined position through the shell with an escape end above the top, a spreader having a communicating connection with the shell through the bottom of the shell for an intake and having another communicating connection with an additional heating element for an outlet, said heating element extending through a large part of the length of the flue with an outlet into the shell through the side of the flue near the top of the shell, and a water softening means in the shell approximately parallel to the flue and having an inlet and means to discharge into the shell, the shell having an outlet for water coming from the softening means.

2. In a water heater and softener, a shell of elongated form with bottom and top, means for heating the contents of said shell, a casing for a water softener in the shell and extending above said top, filtering mediums and softening mediums disposed in the casing, an inlet connection extending from the top of the casing through the softening and filtering mediums, an outlet connection having communication at a point above the softening and filtering mediums with the shell, and an outlet on the shell.

3. In a water heater and softener, a shell of elongated upright form with bottom and top, means for heating the contents of said shell, a casing for a water softener in the shell and extending above said top, filtering and softening mediums disposed in the casing, an inlet connection extending to a point below the filtering and softening mediums from the top of the casing, an outlet connection having communication with the interior of the casing at a point above the

filtering and softening mediums and having other communication with the shell, an outlet for the shell, and means for reversing the flow through the filtering and softening apparatus.

4. In a water heater and softener, a shell with bottom and top, means for heating the contents of said shell, a casing for a water softener in the shell and extending above said top, filtering and softening mediums disposed in the casing, an inlet connection extending to a point below the filtering and softening mediums from the top of the casing, an outlet connection having communication with the interior of the casing at a point above the filtering and softening mediums and having other communication with the shell, an outlet for the shell, means for reversing the flow through the filtering and softening apparatus, and means for supplying refreshing ingredients to the filtering and softening mediums.

5. In a combined water heater and softener, a shell with bottom and apertured top forming the water heater, means for heating the contents of said shell, a casing with supporting means for holding the casing in the apertured top in the shell, a softening medium in the casing, and communicating means between the interior of the shell and the interior of the casing for passing fresh water from the outside by way of said softener into said heater to be discharged therefrom in form of softened heated water.

6. In a combined water heater and softener, a casing with a flange on the outside near the top end, a shell with bottom and top, the top of said shell having an opening with securing means to removably receive the casing and by which said flange may be secured to the top of said shell, means for heating the contents of said shell, and communicating means between the shell and the casing for circulating water through the combined water softener and heater, there being a water softening medium in said casing.

7. In a water heater and softener, a shell having a bottom and an apertured top, means for

heating the contents of said shell, a casing for the softener, a supporting flange around said casing and near its top, means for securing said flange to the top of said shell and around the aperture in the top of said shell, a cup-like closure for the bottom of said casing, a spacing ring at the lower end of said casing, a perforated disc above said ring, layers of filtering medium above said disc, another perforated disc above said filtering material, a pair of short pipes extending through the bottom closure and terminating just above the upper disc, coupling members on the upper ends of said pipes, said members serving to compress the filtering material between said discs, said spacing ring separating the bottom closure from the lower disc and forming a chamber therebetween, apertures in one of said pipes within said chamber, means for sealing the lower ends of said pipes and for securing them to the closure, a sectional supporting ring secured to the inside wall of said casing near its top, a pair of screens with layers of filtering material between said screens, resting on said sectional ring, a cover for said casing, a ring on the inner face of said cover projecting into said casing and contacting the uppermost screen, thereby forming a chamber between said cover and said screen, a layer of softening material between the upper disc and the lower screen, a pair of long pipes passing through the cover, the screens and the filtering and softening material and connected to the short pipes by said couplings, perforations in the upper end of one long pipe within the space above the upper screen, means for sealing the pipes in the cover and for clamping the top and bottom together, one of the long pipes forming the inlet and the other the outlet of the casing, means for delivering water from the softener directly to the exterior of the shell, and means for delivering water from the softener through the shell to the exterior of the shell.

WILLIAM J. TOWLES.
